MOUNTING AND OPERATING MEANS FOR
VARIABLE INDUCTANCE DEVICESWilliam A. Schaper, Cicero, Ill., assignor to
Johnson Laboratories, Inc., Chicago, Ill., a cor-
poration of Illinois

Application September 26, 1940, Serial No. 358,464

24 Claims. (Cl. 171—242)

The invention pertains to improved mounting and operating mechanism for permeability tuning devices, by which inductance coils are conveniently and cheaply mounted on a supporting plate, which also supports rollers for controlling cables operatively connected with ferromagnetic cores for movement relatively to the inductance coils, all of the parts being of simple and inexpensive construction and of such a nature that needless parts are eliminated.

It is an object of the invention to produce mounting and operating means for permeability tuning devices by which inductance coils are placed on opposite sides of a mounting plate, an operating roller is mounted at one end portion 15 of the plate to drive a cable connected with the ends of ferromagnetic cores movable longitudinally of the coils, the bearings of the roller being preferably stamped sheet metal parts secured to the mounting plate and constructed at the same time to constitute a supporting base for the entire device, the mounting plate also supporting at its other end an idler roller around which a second cable passes and is connected at its ends with the other ends of said ferromagnetic cores, the idler roller being mounted in a recess in the end of the mounting plate and supported for rotation on a flexible resilient rod which not only permits the roller to turn freely as may be required by movement of the operating roller, but also places a desired tension on the cables employed.

The above and other objects of the invention will more fully appear by reference to the accompanying drawing illustrating a preferred embodiment thereof in which:

Fig. 1 shows in plan view a tuning unit in accordance with the invention,

Fig. 2 is a side elevation of the tuning unit shown in Fig. 1,

Fig. 3 is an end elevation of the tuning unit shown in Fig. 2,

Fig. 4 is a vertical sectional view to an enlarged scale of the construction shown in Fig. 2, taken along the line 4—4 of the latter figure, and

Fig. 5 illustrates in fragmental side elevation the manner in which a number of the tuning units may be mounted on a chassis for gang operation.

Similar numerals refer to similar parts throughout the several views.

As shown in Figs. 1, 2 and 3, the invention consists of a central mounting plate 10 of suitable material, for example sheet metal, which has secured to its upper end portion shown in Figs. 2

and 3, two formed sheet metal members 11 and 12 having their mid-portions rigidly secured to the plate 10 in any convenient manner, for example by rivets, the end portions of said members below the said connections being bent at substantially right angles to the plate 10 and extending therefrom in substantially the same plane to constitute the supporting base of the tuning device. The other end portions of the members 11 and 12 are bent into arcuate form as shown at 11a and 12a respectively, to receive and support a driving roller 13 having a shaft 14 to operate the same to in turn move the ferromagnetic cores of the tuning device. The roller 13 comprises a central portion of relatively large diameter and journaled end portions 13a and 13b of substantially smaller diameter, which journaled portions are engaged by the curved portions 11a and 12a of base members 11 and 12. As shown in Fig. 2, the base member 11 is notched at its midportion to clear the central portion of the roller 13, and said member 11 has extending therefrom partly around the journals 13a and 13b, bearing members 11a and 11b, of which only the bearing member 11a is seen in Fig. 3. Similarly, as indicated in dotted lines in Fig. 2, the bearing members 12a and 12b extend from the base member 12 partly around the journals 13a and 13b to form bearing members for said journals. It will be noted that each of the bearing members 11a, 11b, 12a, 12b is slightly narrower than half the axial length of the corresponding journal 13a, 13b as the case may be. This construction not only provides a simple and adequate bearing support for the roller 13, but it also provides a convenient means for limiting the rotation of the roller 13, as follows:

As shown in Fig. 1, the roller 13 has formed on it from its mid-portion and extending somewhat less than half the length of the journal portions 13a and 13b, stop lugs 13c and 13d in line respectively angularly with the bearing members 11a and 12b, but so disposed that they do not at any time engage the bearing members 12a and 11b respectively. The stop lugs 13c and 13d are displaced from each other angularly on the roller 13, so that engagement between said lugs and the ends of the bearing members 11a and 12b will permit rotary movement of the roller 13 to the extent desired to properly operate the tuning devices, from which it will be observed that the bearing and roller construction, although including stop lugs on the roller cooperating with the ends of bearing members encircling enough of the journals of the roller angularly to positively

retain the journals in engagement with the bearing members, permits the angular movement of the roller to be of much greater extent than the angular spacing between the outer ends of the bearing members themselves, by arranging one of the stop lugs to engage the end of one of the bearing members, and the other stop lug to engage the end of a bearing member on the opposite end of the roller, and by further so arranging the bearing members that only the bearing members effective in stopping rotation of the roller 13 are in line angularly with the stop lugs 13c and 13d. A further advantage of the construction is that the two members 11 and 12 are duplicates of each other and may be made by the same tools. As shown in Fig. 1, the members 11 and 12 are slotted at 11c and 12c to permit the ready assembly of the cable 15, which, as shown in Fig. 3, extends one and one-half times around the central portion of the roller 13 and has one of its ends secured to one end of the ferromagnetic core 16 of the device, the other end of the cable 15 as shown in Fig. 4 being secured to one end of the ferromagnetic core 17 of the tuning device.

As shown in Fig. 4, the core 17 is supported for longitudinal movement in a tube 18 of suitable insulating material supporting an inductance coil 19, the tube 18 extending longitudinally of the tuning unit and being supported in place by a bracket 18a of sheet metal secured to the mounting plate 10 in any convenient manner, for example by rivets 20 and 21. The core 16 is arranged to move longitudinally in a tube 23 of insulating material carrying an inductance coil 24, the tube extending longitudinally of the tuning unit and being supported by a bracket 25 of sheet material secured to the mounting plate 10 in any convenient manner, for example by rivets 21 and 22. The rivet 21 conveniently cooperates in holding both of the brackets 18a and 25 in place, and the rivets 21 and 22 preferably engage suitable longitudinal slots in the base portion of the bracket 25, permitting the bracket and coil 24 carried thereby to be moved relatively to the mounting plate 10 and longitudinally of the core 16, to secure any desired adjustment of the coil 24 relatively to and longitudinally of the core 16, for example for aligning or tracking purposes. The lower end portion of the plate 10 is notched to receive an idler roller 26 mounted for rotation on a slender resilient rod 27 of spring material, for example spring steel, supported near its ends by lugs 10a and 10b formed from the plate 10. The roller 26 serves to guide a cable 28 from alignment with the core 16 to the lower end of which it is secured, to alignment with the lower end of the core 17 to which said cable is also secured. The roller and cable construction therefore results in moving the cores 16 and 17 longitudinally and relatively to the coils 24 and 19 respectively in opposite directions, when the shaft 14 is rotated, the stops 13c and 13d being so disposed angularly, and the diameter of the central portion of the roller 13 being so taken, that the maximum desired movement of each of the cores 16 and 17 will result from turning the roller 13 as far in either direction as the stops 13c and 13d will permit. The roller 26 is provided with a clearance hole through it to receive the rod 27, so that the roller may turn freely on the rod, the size of the clearance hole being sufficiently larger than the rod to permit the rod to bend somewhat as illustrated in Fig. 2, to apply suffi-

cient tensional force to the cables 15 and 28 to keep them in a taut condition so that the cores will be operated without lost motion when the shaft 14 is rotated.

5 The plate 10 is preferably provided with a flange portion 10c to support a block of insulating material 29 carrying adjustable capacitors 30 and 31 for cooperation with the coils 24 and 19 respectively for any purposes for which the coils may be used.

10 As shown in Fig. 2, the shaft 14 where it extends through roller 13, is substantially half cut away as indicated at 14a for engagement with a flat bent spring 32 extending through a flat 15 slot 13e formed longitudinally through the roller adjacent the shaft 14, said spring having bent ends holding the spring in place in the roller, when the shaft is also in the roller, for which condition the spring is in a nearly straight and 20 stressed condition holding the shaft against angular displacement relatively to the roller so that turning the shaft 14 will turn the roller 13 to operate the cores 16 and 17. The spring 32 does not, however, prevent the ready insertion of the shaft 14 into and through the roller 13, nor does it prevent the ready removal of the shaft from the roller.

25 As shown in Fig. 2, one edge of the base portion of the bracket 25 is preferably provided with rack teeth 25b adjacent a centering aperture 40 in the plate 10 for cooperation with a suitable pinion tool or the equivalent (not shown), for adjusting the bracket on the plate 10.

30 The roller 13 is preferably made of ceramic material so that it will have desired insulating value, be non-magnetic, and at the same time facilitate the molding of the stop lugs thereon, as well as the molding of the central opening therethrough, so that when the molding and firing are completed, the roller structure is ready for assembly in the tuning device. The roller 26 35 may be of any suitable material, for example ceramic, Bakelite, fiber, or other material adapted to the purpose.

40 The tuning unit construction described in connection with Figs. 1-4 inclusive is well adapted for gang operation as illustrated in Fig. 5, in which a chassis is illustrated at 33 upon which tuning units 10d are mounted, each constructed as described in connection with Figs. 1-4 inclusive, said tuning units being mounted on said chassis so that the operating rollers 13 of said tuning units are the lowermost parts of said tuning devices and are below the top wall of the chassis 33 and secured to said chassis with the said operating rollers 13 in alignment with each other. For this condition, a single operating shaft 14b constructed in a manner similar to the shaft 14 above described, but having a flattened portion of sufficient length to extend through all of the operating rollers 13 used in the assembly illustrated in Fig. 5, is readily inserted through all said operating rollers and cooperates with each roller by means of a flat spring 32 45 in the manner above described, and as a result the rollers 13 are simultaneously operated when the shaft 14b is turned. The shaft 14b is provided with a groove 14c adjacent the side wall of chassis 33, into which a split ring 34 is compressed to prevent the withdrawal of the shaft 14b from the rollers 13, the engagement of the shoulder at the end of the flattened portion of said shaft with the roller 13 nearest the ring 34, preventing longitudinal motion of the shaft 14 50 in the opposite direction. The shaft 14b is ex-

75

tended beyond the ring 34 ar id through the side wall of the chassis to support an operating knob 35 by which the shaft 16b may be turned as desired.

It will be observed that in mounting the tuning units 10d on the chassis 33 as described, the only openings that need be cut through the top wall of the chassis are openings large enough to clear the rollers 13 and 14 that when the tuning units are in place on the chassis, the base members 11 and 12 of the tuning units cover said openings to thus completely enclose the wiring and accessory devices contained in the chassis 33, to avoid fire hazards as required by the authorities. With a gang assembly of tuning units as illustrated in Fig. 5, shield plates 36 are required between the units, if they are mounted in closely associated relation, but it will be observed that there is no need to employ shield cans for said units unless it is necessary to shield the coils of the units from other parts of the apparatus or to prevent outside inductive effects in operating the coils of the tuning units. It will also be observed in connection with each of the tuning units, that the mounting plate 10 serves as a shield plate between the two coils of the unit so that there is no appreciable coupling or interaction between the coils of the unit.

The tuning units described being each self contained, may be mounted in any position desired, whether horizontal, vertical, or otherwise, and with the units extending in any desired directions from their operating shafts, without in any way changing the operation of said units or the effects secured by said operation.

The cables 15 and 28 may be of any material adapted to the purpose, for example cord or wire, or other fibrous or metallic material, the only requirements being that it shall be sufficiently flexible to bend freely around the rollers and that it shall in no way interfere with the operation of the tuning units.

It will be understood that while the invention is herein illustrated as embodied in a tuning unit construction adapted to simultaneously tune a pre-selector circuit and an oscillator circuit of a superheterodyne radio receiver, over a desired range of frequencies, the invention is not limited to that purpose, for by suitably winding the coils and suitably selecting the cores, and connecting the flexible cables to the cores in the manner required in any particular case to secure a desired relation of inductance variation of the coils, the invention may be used effectively in any case where it is required to change or vary the inductances of two circuits, whether the change is in the same direction as illustrated, or in an opposite direction.

While I have shown my invention in the particular embodiment above described, I do not limit myself thereto as I may employ equivalents thereof without departing from the scope of the appended claims.

Having thus described my invention, what I claim is:

1. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, and a second flexible cable extending around said idler roller and having its ends connected respectively with the other ends of said cores, whereby turning said operating roller moves each of said cores relatively to the associated coil.
2. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, and a flexible rod of resilient material extending through a central clearance hole in said idler roller and supporting said idler roller for angular movement, the end portions of said rod being held by said plate with said rod in a condition of stress tensioning said cables.
3. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, and a flexible rod of resilient material extending through a central clearance hole in said idler roller and supporting said idler roller for angular movement, said plate having bent and integral lugs holding the end portions of said rod.
4. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil.

ciated coil, and a flexible rod of resilient material extending through a central clearance hole in said idler roller and supporting said idler roller for angular movement, said plate having bent and integral lugs holding the end portions of said rod with said rod in a condition of stress tensioning said cables.

5. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, and sheet metal bearing members secured to the end portion of said plate and having arcuate end portions constituting bearings for said operating roller.

6. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, and sheet metal bearing members secured to the end portion of said plate and having arcuate end portions constituting bearings for said operating roller, said bearing members being on opposite sides of said plate and the other end portions of said bearing members being bent and extending in substantially the same plane and in opposite directions from said plate to constitute a mounting base for said tuning unit.

7. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the asso-

ciated coil, and sheet metal bearing members secured to the end portion of said plate and having arcuate end portions constituting bearings for said operating roller, said bearing members being on opposite sides of said plate and the other end portions of said bearing members being bent and extending in substantially the same plane and in opposite directions from said plate to constitute a mounting base for said tuning unit, said bearing members being of identical size and form.

8. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, sheet metal bearing members secured to the end portion of said plate and having arcuate end portions constituting bearings for said operating roller, and stop lugs carried by said operating roller for engagement with said bearing members and limiting rotary movement of said operating roller.

9. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, sheet metal bearing members secured to the end portion of said plate and having arcuate end portions constituting bearings for said operating roller, and stop lugs carried by said operating roller for engagement with said bearing members and limiting rotary movement of said operating roller, said operating roller and said stop lugs comprising a unitary structure of molded material.

10. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and

having its ends connected respectively with first ends of said cores, a second flexible cable extending around said idler roller and having its ends connected respectively with the other ends of said cores, whereby turning said operating roller moves each of said cores relatively to the associated coil, sheet metal bearing members secured to the end portion of said plate and having arcuate end portions constituting bearings for said operating roller, and stop lugs carried by said operating roller for engagement with said bearing members and limiting rotary movement of said operating roller, said bearing members being on opposite sides of said plate, and said arcuate end portions being each of less width than the axial extent of the corresponding journal portion of the operating roller, said arcuate end portions of one of said bearing members being spaced axially of said operating roller from alignment with the arcuate end portions of the other of said bearing members, and each of said stop lugs being in alignment with an arcuate end portion of one of said bearing members for motion-limiting engagement therewith and also being free from motion-limiting engagement with the others of said bearing members.

11. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, sheet metal bearing members secured to the end portion of said plate and having arcuate end portions constituting bearings for said operating roller, and stop lugs carried by said operating roller for engagement with said bearing members and limiting rotary movement of said operating roller, said bearing members being on opposite sides of said plate, and said arcuate end portions being each of less width than the axial extent of the corresponding journal portion of the operating roller, said arcuate end portions of one of said bearing members being spaced axially of said operating roller from alignment with the arcuate end portions of the other of said bearing members, and each of said stop lugs being in alignment with an arcuate end portion of one of said bearing members for motion-limiting engagement therewith and also being free from motion-limiting engagement with the others of said bearing members, said bearing members being of identical size and form.

12. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an

idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, sheet metal bearing members secured to the end portion of said plate and having arcuate end portions constituting bearings for said operating roller, and stop lugs carried by said operating roller for engagement with said bearing members and limiting rotary movement of said operating roller, said bearing members being on opposite sides of said plate, and said arcuate end portions being each of less width than the axial extent of the corresponding journal portion of the operating roller, said arcuate end portions of one of said bearing members being spaced axially of said operating roller from alignment with the arcuate end portions of the other of said bearing members, and each of said stop lugs being in alignment with an arcuate end portion of one of said bearing members for motion-limiting engagement therewith and also being free from motion-limiting engagement with the others of said bearing members, the other end portions of said bearing members being bent and extending in substantially the same plane and in opposite directions from said plate to constitute a mounting base for said tuning unit.

13. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, sheet metal bearing members secured to the end portion of said plate and having arcuate end portions constituting bearings for said operating roller, and stop lugs carried by said operating roller for engagement with said bearing members and limiting rotary movement of said operating roller, the end journal portions of said operating roller being of smaller diameter than the central portion thereof and said lugs extending radially from said journal portions.

14. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and

having its ends connected respectively with first ends of said cores, a second flexible cable extending around said idler roller and having its ends connected respectively with the other ends of said cores, whereby turning said operating roller moves each of said cores relatively to the associated coil, sheet metal bearing members secured to the end portion of said plate and having arcuate end portions constituting bearings for said operating roller, and stop lugs carried by said operating roller for engagement with said bearing members and limiting rotary movement of said operating roller, the end journal portions of said operating roller being of smaller diameter than the central portion thereof and said bearing members restraining said operating roller from axial movement relatively to said bearing members.

15. In a tuning unit, the combination of a central mounting plate of sheet metal extending longitudinally of said unit, an inductance coil mounted on each side of said plate and extending longitudinally of said unit, a ferromagnetic core associated with and movable longitudinally of each of said coils for inductance changing purposes, an operating roller mounted for rotary movement at one end portion of said plate, an idler roller mounted for rotary movement at the other end portion of said plate, a first flexible cable extending around said operating roller and having its ends connected respectively with first ends of said cores, a second flexible cable extending around said idler roller and having its ends connected respectively with the other ends of said cores, whereby turning said operating roller moves each of said cores relatively to the associated coil, said operating roller having a flat-sided central hole extending axially through it, a flat-sided operating shaft in said hole, and a flat spring in said hole and pressing against said shaft and said operating roller.

16. In a tuning unit, the combination of a sheet metal mounting plate supporting on each of its sides an inductance coil and an associated ferromagnetic core movable longitudinally of said plate and relatively to the coil for inductance changing purposes, two flexible cables connected with said cores to operate the same, an operating roller mounted at one end portion of said plate and engaging one of said cables, an idler roller mounted at the other end portion of said plate and engaging the other of said cables, and arcuate sheet metal bearing elements carried by said plate and extending around and supporting said operating roller for angular movement.

17. In a tuning unit, the combination of a sheet metal mounting plate supporting on each of its sides an inductance coil and an associated ferromagnetic core movable longitudinally of said plate and relatively to the coil for inductance changing purposes, two flexible cables connected with said cores to operate the same, an operating roller mounted at one end portion of said plate and engaging one of said cables, an idler roller mounted at the other end portion of said plate and engaging the other of said cables, and arcuate sheet metal bearing elements carried by said plate and extending around and supporting said operating roller for angular movement, there being two of said bearing elements at each end portion of said operating roller and spaced substantially axially from alignment with each other.

18. In a tuning unit, the combination of a

sheet metal mounting plate supporting on each of its sides an inductance coil and an associated ferromagnetic core movable longitudinally of said plate and relatively to the coil for inductance changing purposes, two flexible cables connected with said cores to operate the same, an operating roller mounted at one end portion of said plate and engaging one of said cables, an idler roller mounted at the other end portion of said plate and engaging the other of said cables, arcuate sheet metal bearing elements carried by said plate and extending around and supporting said operating roller for angular movement, there being two of said bearing elements at each end portion of said operating roller and spaced substantially axially from alignment with each other, and a stop carried by each end portion of said operating roller for rotation-limiting engagement with one of said bearing elements.

19. In a tuning unit, the combination of a sheet metal mounting plate supporting on each of its sides an inductance coil and an associated ferromagnetic core movable longitudinally of said plate and relatively to the coil for inductance changing purposes, two flexible cables connected with said cores to operate the same, an operating roller mounted at one end portion of said plate and engaging one of said cables, an idler roller mounted at the other end portion of said plate and engaging the other of said cables, and a flexible resilient rod extending through a clearance opening in said idler roller and supporting said roller for angular movement, said plate having engagement with the end portions of said rod and supporting said rod in stressed condition, thereby maintaining said cables in taut condition.

20. In an assembly of self-contained tuning units each completely housed and separately operative and each including inductance coils and ferromagnetic cores movable relatively thereto for inductance changing purposes, and also including flexible cables and operating rollers for simultaneously operating said cores by means of said cables, the operating roller of each unit having its own supporting bearings constituting a part of said unit, the combination of a chassis, a plurality of said tuning units mounted side by side on said chassis, said operating rollers one for each of said tuning units being mounted in axial alignment with each other, each of said rollers having a flat-sided opening extending axially therethrough, and a flat-sided operating shaft extending through all of said rollers for simultaneously rotating the same, said shaft being freely movable axially through said operating rollers for assembling and dismantling purposes.

21. In a tuning unit, the combination of a central mounting plate of sheet metal extending longitudinally of said unit, an inductance coil mounted on said plate and extending longitudinally of said unit, a ferromagnetic core associated with and movable longitudinally of said coil for inductance changing purposes, an operating roller mounted for rotary movement at one end portion of said plate, an idler roller mounted for rotary movement at the other end portion of said plate, a flexible connection extending around said operating roller and said idler roller and connected with the ends of said core, whereby turning said operating roller moves said core relatively to said coil, and a flexible rod of resilient material extending through a central clearance hole in said idler roller and support-

ing said idler roller for angular movement, the end portions of said rod being held by said plate with said rod in a condition of stress tensioning said flexible connection.

22. In a tuning unit, the combination of a central mounting plate of sheet metal extending longitudinally of said unit, an inductance coil mounted on said plate and extending longitudinally of said unit, a ferromagnetic core associated with and movable longitudinally of said coil for inductance changing purposes, an operating roller mounted for rotary movement at one end portion of said plate, an idler roller mounted for rotary movement at the other end portion of said plate, a flexible connection extending around said operating roller and said idler roller and connected with the ends of said core, whereby turning said operating roller moves said core relatively to said coil, and sheet metal bearing members secured to the end portion of said plate and having arcuate end portions constituting bearings for said operating roller.

23. In a tuning unit, the combination of a central mounting plate of sheet metal extending longitudinally of said unit, an inductance coil mounted on said plate and extending longitudinally of said unit, a ferromagnetic core associated with and movable longitudinally of said coil for inductance changing purposes, an operating roller mounted for rotary movement at one end portion of said plate, an idler roller mounted for rotary movement at the other end portion of said plate, a flexible connection extending around

said operating roller and said idler roller and connected with the ends of said core, whereby turning said operating roller moves said core relatively to said coil, sheet metal bearing members secured to the end portion of said plate and having arcuate end portions constituting bearings for said operating roller, and stop lugs carried by said operating roller for engagement with said bearing members and limiting rotary movement of said operating roller, said operating roller and said stop lugs comprising a unitary structure of molded material.

24. In a tuning unit, the combination of a central mounting plate of sheet metal extending longitudinally of said unit, an inductance coil mounted on said plate and extending longitudinally of said unit, a ferromagnetic core associated with and movable longitudinally of said coil for inductance changing purposes, an operating roller mounted for rotary movement at one end portion of said plate, an idler roller mounted for rotary movement at the other end portion of said plate, and a flexible connection extending around said operating roller and said idler roller and connected with the ends of said core, whereby turning said operating roller moves said core relatively to said coil, said operating roller having a flat-sided central hole extending axially through it, a flat-sided operating shaft in said hole, and a flat spring in said hole and pressing against said shaft and said operating roller.
